UNITED STATES PATENT OFFICE.

JOSEPH N. WIGGIN, OF ORANGE, NEW JERSEY.

DESIGN FOR FABRIC.

SPECIFICATION forming part of Design No. 26,665, dated February 16, 1897.

Application filed December 31, 1896. Serial No. 617,680. Term of patent 14 years.

To all whom it may concern:

Be it known that I, JOSEPH N. WIGGIN, a citizen of the United States, residing at Orange, in the county of Essex and State of New Jersey, have invented and produced a new and original Design for Fabrics, and adapted to be printed, placed on, or worked into fabrics for covering walls, books, boxes, and for other purposes, of which the following is a full, clear, and exact description, reference being had to the accompanying drawing, which forms a part of this specification.

In the accompanying drawing the figure is a plan view of my design as applied to a piece of fabric.

The leading feature of my design consists of numbers of wavy irregular elongated stripes having between them spaces of contrasting shades and presenting an ondoyant or irregular appearance or effect.

The design is intended to be printed, placed on, or worked into the fabric in appropriate colors.

What I claim as new is—

The design for a fabric, substantially as herein shown and described.

JOSEPH N. WIGGIN.
